UNITED STATES PATENT OFFICE.

CHARLES H. JOHNSON, OF CHICAGO HEIGHTS, ILLINOIS, ASSIGNOR, BY MESNE ASSIGNMENTS, TO THE PITTSBURG PNEUMATIC COMPANY, OF CANTON, OHIO, A CORPORATION OF NEW JERSEY.

FLUID-PRESSURE-OPERATED TOOL.

No. 887,095.

Specification of Letters Patent.

Patented May 12, 1908.

Application filed November 19, 1902, Serial No. 131,948. Renewed September 8, 1906. Serial No. 333,442.

To all whom it may concern:

Be it known that I, CHARLES H. JOHNSON, a citizen of the United States, residing at Chicago Heights, county of Cook, State of Illinois, have invented a certain new and useful Improvement in Fluid - Pressure - Operated Tools, and declare the following to be a full, clear, and exact description of the same, such as will enable others skilled in the art to which it pertains to make and use the same, reference being had to the accompanying drawings, which form a part of this specification.

My invention relates generally to fluid pressure operated tools, and more particularly to valve mechanism controlling the admission and exhaust of fluid pressure to the cylinder.

In fluid pressure tools it is desirable that the valve controlling the supply and exhaust of pressure to the ends of the cylinder should be operated to cut off the supply from the respective sides of the piston before it reaches the end of its stroke, and it is also desirable that the valve should be quickly shifted from one position to the other, and when shifted, positively held by a preponderance of pressure in each position until the piston reaches the predetermined point in its stroke, when the supply and exhaust of fluid pressure to the respective ends of the cylinder should be reversed.

Fluid pressure operated tools of the character referred to are of such power that if the throttle valve is open when the snap or die is out of contact with the object being worked upon, the snap will be violently ejected from the cylinder and thrown a considerable distance owing to the impact of the piston therewith. It is therefore desirable that the reciprocation of the piston should be automatically prevented when the snap is not in contact with an object.

An object of my invention is to provide a fluid pressure operated tool in which the supply and exhaust of pressure to the respective ends of the cylinder are controlled by a piston valve, the reciprocation of which to its controlling positions will be quickly and certainly accomplished and which when shifted will be firmly held in each position until again shifted by the piston reaching the proper predetermined point in its throw.

A further object of my invention is to construct a fluid pressure operated tool of the character referred to in which the front end

of the cylinder will be automatically connected with the atmosphere when the snap is not in contact with an object, thereby preventing the reciprocation of the piston towards the snap.

A still further object of my invention is to provide a fluid pressure operated tool of the type referred to which will be comparatively simple in construction and efficient in operation.

My invention generally stated consists in a cylinder within which a piston is reciprocated by the supply and exhaust of pressure to its opposite sides, the supply and exhaust of pressure being controlled by a differential piston valve having radial surfaces one of which is constantly exposed to fluid pressure admitted to the valve casing from the supply port to retain the valve in one position, the valve being moved to such position by exposing an end thereof to fluid pressure passing from one end of the cylinder, said valve having a second radial surface of greater effective area than the first surface which is exposed to pressure admitted to the valve casing from the supply port to move the valve to its opposite position, said second radial surface being exposed to fluid pressure in one end of the cylinder to retain the valve in its second position and being relieved of pressure when said end of the cylinder communicates with the exhaust port, thereby permitting the valve to be retained in its first position by the constant pressure exerted on the first radial surface.

My invention further consists in a fluid pressure operated tool in which a button is interposed between the piston and the die to transmit the impact of the former to the latter and to control an exhaust port leading from the front of the cylinder, the button being automatically moved to open the exhaust port to relieve the pressure under the piston when the die is disengaged from an object, thereby preventing the die from being ejected from the cylinder by the piston and also discontinuing the reciprocation of the piston.

The invention will be more fully described hereinafter with reference to the accompanying drawings in which the same is illustrated as embodied in a convenient and practical form, and in which—

Figure 1 is a longitudinal vertical section of an embodiment of my invention taken on line 1—1, Fig. 2, the parts being shown in the

positions they assume when the die is in contact with an object; Fig. 2 a horizontal sectional view of my invention taken on line 2—2, Fig. 1, the parts being shown in the positions they assume when the die is disengaged from an object; Fig. 3 a sectional view on an enlarged scale through the valve casing; Fig. 4 a view similar to Fig. 3 showing the valve in its second position; Fig. 5 a detail sectional view taken on line 5—5, Fig. 3; and Fig. 6 a longitudinal section through the valve.

The same reference characters are used to indicate the same parts in the several figures 15 of the drawings.

Reference letter A indicates the handle of the tool which is provided with a tubular extension A' surrounding the back end of the cylinder C. A lever A⁴ is pivotally supported 20 in the handle A and is provided with a lug a⁴ adapted to engage the end of a valve stem b⁴. The throttle valve is located within a cylindrical valve casing B² which is in screw threaded engagement with an opening B' in the valve handle. A spring B³ is interposed 25 between the valve and the cylindrical valve casing and normally retains the valve in position to close the ports b² formed through the valve seat. A passage B is formed in the handle A and is adapted to be connected with a conduit leading from a source of fluid pressure.

The cylinder C is provided with a bushing c one end of which is engaged by a cylinder head C' which is secured within the end of the cylinder. The handle is retained upon the cylinder by means of an annular flange A⁶ interposed between the end of the cylinder and a peripheral flange on the cylinder head C'. 40 Any suitable means may be provided for preventing the disengagement of the cylinder head from the cylinder, such means being shown as consisting in a spring bolt A⁵ which engages the periphery of the cylinder head. 45 and prevents the same from rotating with respect to the handle.

The end of the cylinder opposite to the cylinder head C' is interiorly screw threaded and is engaged by a ferrule G. A snap or die 50 H is removably supported within the ferrule G and is yieldingly retained therein by means of a spring ring g seated within an annular groove formed in the interior surface of the ferrule near the outer end thereof. The shank 55 of the die H is reduced, as shown at h, forming shoulders at either side of such reduced portion which serve as stops to engage the spring ring g. A chamber C⁴ is formed in the end of the cylinder between the ferrule and 60 the end of the bushing c. Within the chamber C⁴ is located a button L having a reduced portion L' of a diameter substantially the same as the interior diameter of the ferrule within which it extends. An exhaust port 65 l' leads from the chamber C⁴ and is normally

closed by the button L, as shown in Fig. 1, when the die is in engagement with an object. A groove l² is formed in the interior wall of the chamber C⁴ to permit fluid pressure to pass around the head of the button L when the same is in the position shown in Fig. 1. A spring C³ is located between the bushing c and the cylinder C and engages the button L. The tension of the spring tends to move the button to the position shown in Fig. 2 in which the exhaust port l' is opened.

A cylindrical valve casing A² preferably formed integrally with the handle is located transversely beneath the back end of the cylinder. The valve casing is provided with a series of annular grooves with which communicate ports a', a², a³, and a⁴, registering with ports c', c², c³, and c⁴ formed in the cylinder C. Exhaust ports a⁵ and a⁶ are formed in the opposite ends of the valve 85 casing. Supply ports a are located near the center of the valve casing and communicate with a passage A⁶ formed in the handle extending from a point above the throttle valve.

C² is a passage running longitudinally of 90 the cylinder and connecting the port a² with the graduated ports c².

The port c' communicates with a passage leading to a point c⁷ within the cylinder slightly further away from the chamber C⁴ 95 than the length of the piston K as shown in Fig. 2. The port c² communicates with the cylinder near the back end thereof. A plurality of such ports c² of gradually increasing size are preferably employed, as 100 shown in Figs. 1 and 2. The port c³ is extended to form a passage, as shown in Fig. 5, which communicates with the interior of the cylinder at a point c⁶ located the same distance from the rear end of the cylinder as the 105 rear port of the series c². The port c⁴ communicates with a passage leading to the front end of the cylinder.

A bushing E is located within the valve casing A² and is retained therein by means of 110 the cap A³ which closes the open end of the valve casing. One end of the bushing is closed by means of a disk E' while the other end of the bushing is provided with a concentric portion E² which reduces the bore of 115 the bushing. The bushing is provided with series of ports e, e', e², e³, e⁴, and e⁶ which register with the corresponding ports a¹, a², a³, a⁴, and a⁵ formed in the valve casing.

A differential piston valve D is located 120 within the bushing and controls the ports therethrough. The end D' of the valve is hollow and is provided with ports d¹, connecting the exterior surface with the hollow interior. A shoulder D³ is formed on the 125 valve by reducing the diameter, as clearly shown in Fig. 6. The end of the valve D² is also hollow and is closed by means of a plug D⁶. An annular flange D⁴ of slightly greater diameter than the annular shoulder D³ is 130

formed between the latter shoulder and the end D^2 of the valve. d^3 and d^4 designate the radial surfaces on the opposite sides of the flange D^4 . A series of ports d extend through 5 the valve to the hollow interior thereof adjacent to the flange D^4 . A series of ports d^2 lead from the hollow interior of the end portion D^2 to the exterior surface thereof. A restricted leakage port d^5 extends through 10 the annular shoulder D^4 .

The several parts of the valve mechanism may be readily assembled by inserting the valve in the bushing prior to placing the end cap E' on the bushing and subsequently inserting the bushing with the valve therein 15 into the valve casing. The cap A^3 is then inserted preferably by means of coöperating screw threads into the end of the valve casing, thereby closing the same.

20 The operation of my invention is as follows: The lever A^4 is forced forwardly and thereby oscillated about its pivot so that the lug a^4 thereon through the interposed valve stem depresses the throttle valve uncovering 25 the ports b^2 . Fluid under pressure then flows from the source thereof through the coupling B , thence through the ports b^2 to the passageway A^7 which communicates with the annular supply port a located near the 30 center of the valve casing A^2 . When the valve is in the position indicated in Fig. 3 fluid pressure flows from the supply port a inwardly through the ports e in the bushing around the reduced portion of the valve, 35 then outwardly through the port e^2 , in the bushing, the port a^2 in the valve casing, thence through the first of the series of ports c^2 into the back end of the cylinder. As the piston successively uncovers the ports in the 40 series c^2 the impetus of the piston is accelerated owing to the ports in the series c^2 being gradually larger in diameter.

When the piston is to the rear of, or covers the port c^2 , and the valve is in the position 45 shown in Fig. 3 both ends of the valve are exposed to atmospheric pressure, D^2 directly through ports a^6 and D' through the front end of the cylinder by way of ports and passages b' , e' , a' , c' , c^7 , c^4 , a^4 , e^4 and a^6 , while the 50 shoulder D^3 and radial surfaces d^3 and d^4 are all exposed to the same pressure and consequently the valve is retained in this position owing to the area of the radial surface d^4 being greater than the difference in 55 area between the radial surface of the shoulder D^3 and the radial surface d^3 .

When the piston has nearly reached the limit of its forward stroke the port c^2 is uncovered and fluid pressure then flows 60 through the passage communicating with said port to the port c' , thence through the port a' in the valve casing, the ports e' in the bushing, through the ports d' to the hollow interior of the end D' of the valve. The 65 valve is consequently moved from the posi-

tion shown in Fig. 3 to that shown in Fig. 4. This movement of the valve takes place owing to the area of the end D' thereof being greater than the resultant area exposed to pressure in the opposite direction. 70

When the valve is in the position indicated in Fig. 4 the rear end of the cylinder is placed in communication with the exhaust through the following ports and passages; c^2 , a^2 , e^2 , d' and a^6 . Fluid pressure is then admitted to the front end of the cylinder to move the piston towards the handle through the following ports and passages; a , e , d , d^2 , e^4 , a^4 , and port c^4 , which communicates with the front end of the cylinder. 75

When the piston covers port c^4 fluid pressure passing through leakage port d^5 cannot escape to the atmosphere and acts against the radial surface d^4 , and consequently as the area of the radial surface d^4 is greater than 80 the difference in area between the radial surface d^3 and the shoulder D^3 the valve is moved to the position shown in Fig. 3 inasmuch as the opposite ends of the valve are exposed merely to atmospheric pressure directly through ports a^6 and a^6 . While a leakage groove d^5 is shown the same may be omitted without interfering with the operation of the valve as the leakage around the annular flange D^4 is sufficient to effect the reverse movement of the valve from the position shown in Fig. 4 to that shown in Fig. 3. Pressure is now admitted for the forward stroke through ports e^2 , and a^2 and the graduated port c^2 , and the valve is retained in position shown in Fig. 3 by pressure in the cylinder, which backs up in passage c^2 and acts on the radial surface d^4 . 95

When the snap or die is forced against an object the spring C^3 is compressed owing to 100 the engagement between the adjacent end of the die H and the reduced portion L' of the button L . The exhaust port l' is consequently closed when the button L is in position to receive the impact of the piston and transmit the same to the die H . When however the snap or die H is out of engagement with an object the spring C^3 expands, thereby forcing the button to the position shown in Fig. 2, which in turn moves the die outwardly, as indicated in said figure. The exhaust port l' is then uncovered by the button which permits the fluid under pressure to exhaust from the front end of the cylinder to the atmosphere and consequently discontinues the reciprocation of the piston. The movement of the die to the position shown in Fig. 2 owing to the expansion of the spring removes the same from the range of impact of the piston and consequently prevents the die from being ejected from the tool when it is disengaged from an object. 115

From the foregoing description it will be observed that I have invented an improved fluid pressure operated tool employing a pis- 120

ton valve for controlling the supply and exhaust of fluid pressure which is moved to one position by fluid pressure admitted to the valve casing through a passage leading from 5 the interior of the cylinder, and retained in said position by exposing one surface of the valve to the atmosphere through the cylinder, while a second surface is exposed to constant pressure from the supply port and 10 which is moved to and retained in its other position by the pressure of an accumulation of fluid upon the first surface the latter being then cut off from the atmosphere by the piston. It will be further observed that I have 15 provided a fluid pressure actuated tool the front end of which is automatically connected with an exhaust port when the tool is disengaged from an object, thereby discontinuing the reciprocation of the piston, and in which 20 the snap or die is automatically moved out of range of impact of the piston when the tool is out of engagement with an object.

While I have described more or less precisely the details of construction I do not 25 wish to be understood as limiting myself thereto, as I contemplate changes in form, the proportion of parts, and the substitution of equivalents, as circumstances may suggest or render expedient, without departing from 30 the spirit of my invention.

Having now fully described my invention what I claim as new and desire to secure by Letters Patent is—

1. In a fluid pressure operated tool, the 35 combination with a cylinder, of a piston reciprocated therein, a valve casing having a series of ports of graduated sizes communicating with one end of the cylinder and a port communicating with the opposite end of the 40 cylinder, a differential piston valve in said casing controlling the supply and exhaust of pressure through said ports to the opposite ends of the cylinder.

2. In a fluid pressure operated tool, the 45 combination with a cylinder, of a piston adapted to reciprocate therein, a valve casing having ports communicating with said cylinder, a differential piston valve within 50 said casing controlling the supply and exhaust of fluid pressure to and from the cylinder, a radial surface on said valve constantly exposed to fluid pressure tending to move the valve to one position, a second radial surface larger than the first on said valve adapted to 55 be alternately exposed to fluid pressure in the valve casing and to the atmosphere through the cylinder, said valve casing having passages leading therefrom to the interior of the cylinder controlled by the piston to admit 60 fluid pressure to the valve casing to move the valve into said position, and to expose said second radial surface of the valve to atmospheric pressure to effect the retention of the valve in said position, the movement of the 65 valve to and its retention in its other position

being effected by an accumulation of fluid pressure exerted upon said second radial surface when the atmospheric communication from the valve casing through the cylinder is cut off by the piston.

3. In a fluid pressure operated tool, the combination with a cylinder, of a piston adapted to reciprocate therein, a valve casing having ports communicating with said cylinder, a differential piston valve within 70 said casing controlling the supply and exhaust of fluid pressure to and from the cylinder, said cylinder and valve casing having communicating passages through one of which fluid pressure is admitted to the casing 75 from the cylinder and through the other of which fluid pressure is exhausted through the cylinder from the casing thereby effecting the movement of the valve.

4. In a fluid pressure operated tool, the combination with a cylinder, of a piston adapted to reciprocate therein, a valve casing having ports communicating with said cylinder, a differential piston valve within 80 said casing controlling the supply and exhaust of fluid pressure to and from the cylinder, a surface on said valve constantly exposed to fluid pressure, and two other surfaces on said valve one of which is alternately exposed to fluid pressure from the cylinder and to the atmosphere through the valve casing while the other is alternately exposed to the atmosphere through the cylinder and to fluid pressure in the valve casing.

5. In a fluid pressure operated tool, the 90 combination with a cylinder, of a reciprocating piston therein, a die removably fitted in the end of said cylinder and yieldingly retained therein, a button interposed between said piston and die for transmitting the impact of the piston to the die, and means for automatically preventing the impact of the piston from being communicated by the button to the die.

6. In a fluid pressure operated tool, the 100 combination with a cylinder, of a reciprocating piston therein, a die removably fitted in the end of said cylinder, a button interposed between said piston and die to transmit the impact of the former to the latter, a stop extending into the cylinder to limit the movement of the button, and means for forcing the button against said stop when the die is not in contact with an object.

7. In a fluid pressure operated tool, the 110 combination with a cylinder, of a reciprocating piston therein, a die removably fitted within said cylinder, a button interposed between said piston and die, a stop extending into the cylinder to limit the movement of 115 the button, and a spring engaging said button to force the same against said stop when the die is not in contact with an object.

8. In a fluid pressure operated tool, the combination with a cylinder having a port 120

therethrough, of a reciprocating piston in said cylinder, a die movably fitted in said cylinder, and a spring actuated button closing said port through the cylinder when the die is forced against an object and uncovering said port when the die is not in contact with an object.

9. In a fluid pressure operated tool, the combination with a cylinder having a port therethrough, of a reciprocating piston in said cylinder, a die movably fitted in said cylinder, a button located within the end of said cylinder and interposed between said piston and die, a spring engaging said button whereby the die when forced against an object compresses said spring and moves said button over said port and when the die is disengaged from an object said spring expands and thereby moves said button to uncover the port.

10. In a fluid pressure operated tool, the combination with a cylinder having an exhaust port therethrough, of a reciprocating piston in said cylinder, a die movably fitted in the end of said cylinder, and a spring actuated button interposed between said piston and die for automatically closing and opening said exhaust port when the tool is respectively pressed against and out of contact with an object.

11. In a fluid pressure actuated device, the combination with a cylinder, of a reciprocating piston within the cylinder, a valve chamber, a valve within said chamber controlling the supply and exhaust of motive fluid to and from said cylinder to reciprocate the piston, said cylinder having a pressure supply passage controlled by the piston and leading thereto from the valve chamber for exhausting fluid pressure from the chamber, and said valve having a surface against which pressure accumulates when said passage is closed to the atmosphere.

12. In a fluid pressure actuated device, the combination with a cylinder, of a reciprocating piston within the cylinder, a valve chamber, a valve within said chamber controlling the supply and exhaust of motive fluid to and from said cylinder to reciprocate the piston, said cylinder having an exhaust passage and a pressure supply passage con-

nected the same with the valve chamber said passages controlled by the piston to exhaust fluid pressure from the chamber through the cylinder, and said valve having a surface against which pressure accumulates when said passages are closed by the piston.

13. In a fluid pressure actuated device, the combination with a cylinder, of a reciprocating piston within the cylinder, a valve chamber, a valve within said chamber controlling the supply and exhaust of motive fluid to and from said cylinder to reciprocate the piston, said cylinder having a pressure supply passage controlled by the piston and leading thereto from the valve chamber for exhausting fluid pressure from the chamber, and said valve having a surface against which pressure accumulates when said passage is closed to the atmosphere, to move the valve to a certain position.

14. In a fluid pressure actuated device, the combination with a cylinder, of a reciprocating piston within the cylinder, a valve chamber, a valve within said chamber controlling the supply and exhaust of motive fluid to and from said cylinder to reciprocate the piston, said cylinder and valve chamber being connected by a passage through which fluid pressure is exhausted from the chamber through the cylinder to control the valve.

15. In a fluid pressure actuated device, the combination with a cylinder, of a reciprocating piston within the cylinder, a valve chamber, a valve within said chamber controlling the supply and exhaust of motive fluid to and from said cylinder to reciprocate the piston, said cylinder and casing having ports and passages through which the reciprocation of the valve is effected comprising a passage controlled by the piston and connecting the cylinder with the pressure supply passage of the valve chamber through which pressure is exhausted when uncovered by the piston and within which pressure accumulates when closed by the piston.

In testimony whereof, I sign this specification in the presence of two witnesses.

CHARLES H. JOHNSON.
